United States Patent

Des. 239,837
Patented May 11, 1976

239,837

BATTERY COVER

Roy Erving Hennen, Mequon, Wis., assignor to
Globe-Union Inc., Milwaukee, Wis.

Filed Jan. 20, 1975, Ser. No. 543,016

Term of patent 14 years

Int. Cl. D13—02

U.S. Cl. D26—6

Fig. 1

Fig. 2

Fig. 3

Fig. 4

FIG. 1 is a perspective view of a battery cover incorporating my new design;

FIG. 2 is a front elevational view thereof;

FIG. 3 is an elevational view taken from one end thereof, the opposite end being a mirror image of the end shown; and

FIG. 4 is a rear elevational view thereof.

The fragmentary broken line representation of a battery case in FIG. 1 is for purposes of illustration only.

I claim:

The ornamental design for a battery cover, as shown and described.
